UNITED STATES PATENT OFFICE.

BRUNO V. NORDBERG, OF MILWAUKEE, WISCONSIN, ASSIGNOR TO THE BRUNO NORDBERG COMPANY, OF SAME PLACE.

STEAM-PUMP.

SPECIFICATION forming part of Letters Patent No. 433,992, dated August 12, 1890.

Application filed August 10, 1887. Serial No. 246,637. (No model.)

To all whom it may concern:

Be it known that I, BRUNO V. NORDBERG, of Milwaukee, in the county of Milwaukee, and in the State of Wisconsin, have invented certain new and useful Improvements in Steam-Pumps; and I do hereby declare that the following is a full, clear, and exact description thereof.

My invention relates to steam-pumps, and will be fully described hereinafter.

In the drawings, Figure 1 is an elevation of my improved pump, looking from the rear. Fig. 2 is a section on line *xx* of Fig. 1. Fig. 3 is a section taken through line *yy*, Fig. 4. Fig. 4 is a section on line *zz*, Fig. 1. Fig. 5 is a vertical central section, and Fig. 6 a horizontal section, of a modified form of my invention. Fig. 7 is a side elevation of my device, showing in connection therewith devices for adjusting the two pistons with relation to each other; and Fig. 8 is a horizontal section on the dotted line shown in Fig. 7.

A is the outer shell or casing of my pump, and A' its base. The shell or casing A is formed with two compartments B, which extend from the bottom of the casing to the partition *c*, that separates it from the outlet-chamber *b*.

C is a partition that separates the compartments B from each other. On each side of the partition C the shell is provided with a flange *d*, which forms a short cylinder, and each cylinder *d* has a port *e*, that opens upward from the rear, and from the inner termination of the cylinder *d* ribs *d'* extend to the partition C and form guides for the heads D of the pistons D' and D² after they leave the cylinders *d* in their forward stroke.

Above the path of each piston-head D is arranged a chamber E, which opens from inlet-port G and leads through suction-valves E' into another chamber F, which latter are each connected with the rear of its subjacent cylinder by a port *e*, and through cylinders *d* each with a chamber B. The chambers B and F on each side also communicate with each other through valves *f*, just beneath the outlet-chamber, and chambers B communicate with the outlet-chamber *b* through valves *g*.

The pistons D' and D² are connected by a

cross-head H and rods K, or in any other suitable manner, and piston D² is coupled to the piston D' of the steam-engine, as shown in Fig. 8.

As steam is let into the steam-cylinder my improved pump will operate as follows: Suppose piston D' is in its extreme position and ready for forward stroke and piston D² ready for backward stroke, and the pump is filled with fluid, with the valves all down in their seats. Now as piston D' is drawn forward by the piston of the engine we find that while the piston-head is in the cylinder *d* it will force the fluid through chamber B and up through valves *g* into the discharge-chamber *b* in a volume equal to the displacement of the piston-head, and fluid will be drawn by it through port *e* from the chamber F, and through the valves E' from chamber E, which valves are therefore opened during this part of the stroke, as are also the discharge-valves *g*, while the valves *f* are closed by the pressure of fluid in the chamber B above them.

We have also during this part of the stroke full pressure on the piston D', corresponding to the pressure in the discharge-pipe multiplied by the full area of the piston-head, and also the full steam-pressure in the steam-cylinder; but when the piston-head passes out of the cylinder *d* the steam is cut off from the steam-cylinder and the chambers on each side of the pump-piston head D come in communication with each other, and then the pressure on each side thereof is equalized—that is, we get the discharge-pressure on the back side of the piston, which closes the valves E'—and during the rest of the stroke the volume of fluid discharged is equal to the displacement of the plunger, and the fluid will be forced through valves *g* into the chamber *b* in volume equal to the displacement of the piston-rod or plunger.

The final pressure of the expanding steam on the steam-piston must be equal to or greater than the pressure on the piston D', which during this part of the stroke corresponds to the pressure in the discharge-pipe multiplied by the area of the piston-rod or plunger. In its backward stroke plunger D' as it retires will increase the space in chamber B in proportion to the bulk of the plunger withdrawn, and create suction

through chambers E and F until the piston-head enters cylinder d, and then the fluid in chamber F will be forced out through valves f into chamber B, and at the same time fluid 5 will be drawn into F from E and be ready to be expelled by the next forward stroke. Each piston-head has a short plunger L in front of it, which fits in a short cylinder M on the partition C, and these cylinders are connected at 10 their sides each with a chamber B by a pipe N, having a suitable valve or cock, by which the water in the cylinder M is regulated in its escape to give the proper amount of cushioning resistance to the plunger.

15 While I have shown my invention as applied to a double-acting pump, it is obvious that it can be equally as well applied to a single-action pump or to a double or single acting upright plunger.

20 While my pump is sufficiently powerful for all uses, it is economical, in that I am enabled for the greater part of each stroke to use steam expansively. Instead of extending the cylinder d by ribs d', I may simply use a 25 cylinder that is perforated for part of its length.

In the modification shown in Figs. 5 and 6 the pistons are connected with each other and with the engine-piston, as before described; 30 but the valves f are omitted and the top of chamber F is made solid, so that the only communication between chambers B and F is through ports e and the cylinders d. The piston-heads D are made hollow, each having 35 a cross-piece p, and are connected to the ends of the pistons by bolts p', each of which secures a flexible valve P and a cup-washer P' to each piston, the convex portion of each washer P' lying next to its valve and being 40 sufficiently remote from it to permit the valve to open far enough for its purposes.

In operation from the time piston D', for instance, begins to advance until it has carried the head D out of its cylinder d the water will be drawn by suction from the chamber E through valves E' and chamber F, and after that the displacement of the piston as it enters will close valves E' and force water out through valves g until the stroke is finished, and then on the return-stroke the retiring piston, leaving a vacuum, will again cause suction through valves E, which will continue until the stroke is finished, as the valve P, opening outward, will permit a free circulation of water through the piston-head. 55

Figs. 7 and 8 are to illustrate one method of adjusting the pistons in a double-acting pump with relation to each other and the engine-piston to determine the point in the 60 stroke of the pump-pistons at which direct steam-pressure shall cease and expansive pressure shall begin. In this instance the piston-rod D³ of the motor is provided with right-hand threads at its end next the pump,

while the adjacent end of the pump-piston D² 65 has a left-hand thread, the latter being double the pitch of the former. Both are tapped into a sleeve Q in the cross-piece H, and each has a limiting-nut s, while the sleeve Q is held in the cross-piece H by a nut R. If it is desired 70 to adjust the pump for an earlier cut-off than the device is set for in Fig. 8 of the drawings, it will be necessary to bring the pump-pistons closer together, that they may sooner leave the solid part d of the cylinder and sooner establish an equilibrium. To do this, it is necessary to loosen the nuts R and s and turn the sleeve Q to the right when looking at the the sleeve from the steam end of the pump, when both guide-rods and pump-pistons will be 80 drawn toward the steam-cylinder a certain distance, but at the same time.

Having thus fully described my invention, what I claim as new, and desire to secure by Letters Patent, is—

1. The combination, with the suction and delivery chambers of a steam-pump, of a cylinder opening at one end to the suction-chamber and at the other to the delivery-chamber, and a piston working in and out of said cylinder, adapted for separating the suction and delivery chambers from each other during part of its stroke and for establishing communication between them during the remainder of the stroke, substantially as described. 90

2. In a steam-pump, a cylinder having a port leading from the suction-chamber, and an extension that communicates with the delivery-chamber, in combination with a piston adapted to travel in the cylinder and extension alternately, said piston having a forcing action while in the cylinder proper and a mere displacing action when in the extension, substantially as described, and for the purpose set forth. 100

3. In a steam-pump, two chambers, the first chamber provided with suction and delivery valves, the former sucking from the second chamber, which in its turn communicates with the suction-pipe through the suction-valves, 110 a cylinder open at or near its ends, and a piston traveling therein beyond the open portions for separating the suction from the delivery-chambers during a portion of its stroke and for throwing them into communication 115 during the remainder of the stroke, whereby the piston has at first a forcing action and then a mere displacing action during each stroke, substantially as described.

In testimony that I claim the foregoing I 120 have hereunto set my hand, at Milwaukee, in the county of Milwaukee and State of Wisconsin, in the presence of two witnesses.

BRUNO V. NORDBERG.
